UNITED STATES PATENT OFFICE

STANLEY S. GREEN, OF LA FAYETTE, INDIANA, ASSIGNOR TO DUNCAN ELECTRIC MANUFACTURING COMPANY, OF LA FAYETTE, INDIANA, A CORPORATION OF ILLINOIS

ELECTRIC SWITCH

Application filed August 1, 1929. Serial No. 382,644.

My invention relates to electric switches and has a number of objects and advantages in view.

The invention, in one of its embodiments, relates particularly to an electric switch which is inclusive of a turning member having a contacting blade thereon and a stationary member having two contacting blades thereon positioned to have one end of each engageable by the first mentioned contacting blade that is receivable between the other blades. Instead of relatively positioning the two contacting blades upon the stationary member, as hitherto, I employ clamping means for securing the mounted ends of the blades together, with suitable spacing means therebetween. In the preferred embodiment of the invention the clamping means is in the form of a metallic rod passing through said mounted blade ends and through the spacer therebetween, this spacer being preferably in the form of a metallic washer. The rod is pressed into clamping or holding relation with these two blades and the interposed washer by having its ends upset or riveted. The rod is desirably provided with a threaded bore for the reception of a binding screw. This bore desirably passes throughout the length of the rod, so that a binding screw may be applied at each end, a construction which is advantageous where one conductor is to be permanently connected with one end of the rod and another conductor is to be separably connected with the other end of the rod. My invention finds a very useful embodiment in a switch structure which is associated with the line and load circuits of an electric current consumption system. When a switch is made for this association, the turning member has two contacting blades thereon and a plurality of pairs of stationary contacting blades are provided, the blades of each pair being spaced apart to enable the complementary blade upon the turning member to be snugly received therebetween. There are four such pairs of stationary blades whose anchoring rods or other anchorages are at the corners of a quadrilateral, the axis of the turning member desirably intersecting the intersection of the

diagonals of the quadrilateral. The stationary blades that are secured by these four anchorages extend to the turning member where they are engageable by the blades upon the turning member. The switch may be provided with a fifth stationary pair of blades located abreast of one of the other pairs of blades and held in place, preferably, by the same anchorage.

Generally speaking, such a switch is of a grid or grating formation with its parts of such simple construction that they may be cheaply made and readily assembled. A switch thus organized preferably has two coplanar pairs of contacts which are relatively disposed to have one of the blades upon the turning member complementary to both, all the blades being so proportioned and relatively disposed that the blade upon the turning member is adapted to have simultaneous engagement with the blades of both pairs at the same time. The blade upon the turning member and the blades of both pairs are always in such relation as to receive axial thrusts upon the turning member, making it unnecessary to provide any additional means for receiving such thrusts. When such a switch employs a plurality of contacting blades upon the turning member, there are preferably at least two pairs of stationary blades which are so related to each other and to the blades upon the turning member that some one of these latter blades is received between the contacting blades of the pair individual to it in all positions of the turning member, whereby axial movement of the turning member is further guarded against. A support is desirably added in which the turning member is journaled and which is so simply formed as to permit the turning member to be axially movable were it not for the interrelation of the blades. These structural characteristics permit the employment of end plates of insulation which are held in assembly by the anchorages at the corners of the switch structure, being preferably clamped between the riveted ends of the rods and the switch structure portions that intervene between these rod ends, where anchorages in the form of rods are employed.

These end plates may, if desired, serve as bearings by being provided with circular holes therethrough, of uniform diameter in which the body portion of the turning member, which is also preferably insulation, are journaled.

The aforesaid end plates of insulation also serve as guards to prevent undesirable access to the switch parts that are disposed therebetween. These guards ordinarily would conceal the relative positions of the stationary and rotary contacts making it difficult to observe these contacts to determine the adjustment of the switch. In order that the adjustment of the switch may be readily determined the stationary and turning members thereof are provided with lines thereon, these lines being preferably provided upon the turning member and guard in such relation that when the switch is closed the lines are consecutive and when the switch is open the lines are separated. Thus an animated diagram is provided whereby the circuit adjusting condition of the switch is revealed without the necessity of observing the relationship of the switch contacts.

The switch structure of my invention, in another of its characteristics, is provided with a support, preferably a casing, having one or more contact terminals therein, according to the number of stationary contacts or pairs of stationary contacts which are automatically brought into connection with said stationary contact or contacts when the switch structure is fully received within the casing. I also provide a holder for the turning member to secure it in contact making position. This holder is desirably a cover for the casing. The holder and turning member have interengaging holding formations, eccentric to the axis of the turning member, which secure the turning member in circuit closing position when the holder is in position. The holding formation upon the turning member is desirably a pin and the holding formation upon the cover is then a socket that receives the pin.

The invention will be more fully explained in connection with the accompanying drawings in which Fig. 1 is a perspective view illustrating the preferred form of switching mechanism of my invention and a container therefore, these structures being shown in separated relation; Fig. 2 is a front sectional view taken through a mid-portion of the casing shown, it being assumed that the switch is within the container, in this figure; Fig. 3 is a sectional view on line 3—3 of Fig. 2; Fig. 4 is a sectional view on line 4—4 of Fig. 5; Fig. 5 is a sectional view on line 5—5 of Fig. 4; Fig. 6 is a sectional view on line 6—6 of Fig. 5; Fig. 7 is a sectional view on line 7—7 of Fig. 4; Fig. 8 is a circuit diagram illustrating one of the uses to which the switch of my invention may be put; Fig.

9 is a face view of the switch within its container, the container cover being removed; and Fig. 10 illustrates a slight modification.

The switch illustrated includes a stationary member having five pairs of contacting blades 1, 2; 3, 4; 5, 6; 7, 8; and 9, 10. The blades of each pair are provided with spacing means therebetween, such spacing means being preferably separately formed from the blades and assembled therebetween. In the preferred embodiment of the invention, the spacing means are in the form of metallic washers 11 and the means for anchoring the mounted ends of the blades are in the form of metallic rods 12 of equal length that pass through the aforesaid blades and washers. These rods have reduced end portions which pass through quadrilateral or rectangular insulating plates 13 and 14. The rods are rivet ended, as indicated at 15 and 16, against the plates, the rivet ends of the rods exerting clamping pressure upon the aforesaid blades and washers through the intermediation of said plates. The washers 11 that are alternated with the blades 7, 8, 9 and 10 fill the space between said plates 13 and 14 sufficiently to enable these plates to exert clamping pressure upon said washers and plates with sufficient firmness to hold these four blades in fixed relation with each other and with said plates. Other washers 17 are employed in conjunction with the remaining blades to enable said plates to clamp these blades in place. The riveted ends 15, 16 of the rods thus serve to exert clamping pressure upon the plates 13 and 14, this pressure being transmitted to the washers and blades interposed between the plates. The pairs of blades 3, 4; 5, 6; 7, 8 are coplanar, the spaces between the blades of these three pairs being, therefore, coplanar. The pairs of blades 7, 8 and 9, 10 are abreast of each other on the same anchorage 12. The pairs of blades 1, 2 and 9, 10 are also coplanar, the spaces between the blades of these two pairs being, therefore, also coplanar. The blades are desirably parallel with the long sides of the insulating plates 13 and 14 and terminate slightly short of the plane which contains the median transverse lines or axes of said plates. These plates are desirably just in full lapping relation with the aforesaid blades that are between them, thereby serving as guards for these blades and the contacting blades, later to be mentioned, that are complementary thereto.

The turning member of the switch is preferably inclusive of a cylindrical body portion of insulation 18 which is desirably molded about the anchored sides of the blades 19 and 20. The member 18 is preferably journaled in the plates 13 and 14, being received within circular holes that snugly fit it. A knob 18' is suitably assembled with the front end of the body portion 18, as by means of the

exteriorly smooth pin 18² which passes through it and the solid externally-threaded pin 18³ which is screwed into it, the body 18 being molded about the inner ends of the pins. Said knob may be provided with a screw driver slot 18⁴ for the reception of a turning tool, such as a screw driver or a handy coin. The contacting ends of the stationary blades are arcuately curved adjacent the body portion 18 of the turning member and concentrically with this turning member, the spacing between the turning member and the arcuate portions of the adjacent stationary blades being small. The blades 19 and 20 upon the turning member extend radially beyond the gaps between the member portion 18 and the stationary blades and are of sufficient width to reach the outer longitudinal sides of the stationary blades as the turning member is operated. A withdrawable metallic post 21 is screwed into the plate 14 to cooperate with an insulating tongue 22 upon the turning member to limit the turning movement of the turning member in one direction, the movement of this member in the other direction being limited by the cooperation of this tongue with the inner long side of the blades 9 and 10. The elements 21 and 9 and 10 confine the turning member of the switch to movement through an angle of ninety degrees. The blades 19 and 20 are nearly, but not quite, half circles, the inner or adjacent straight edges of these blades being slightly spaced apart from a plane that is inclusive of the axis of the turning member. When the tongue 22 engages the post 21 said straight edges of the blades 19 and 20 are parallel with the long sides of the stationary blades and are substantially flush with the inner long sides of the stationary blades with respect to which they are complementary. In this adjustment of the turning member, the pair of blades 3 and 4 receives the blade 19 as does also the pair of blades 5 and 6 that are coplanar with the blades 3 and 4, equal portions of the blade 19 being received between both blades of each of these pairs. The blade 20 is similarly received between the blades of the coplanar pairs 1, 2; and 9, 10, and is withdrawn from between the blades 9, 10. The blade 20 thus remains in constant engagement with the blades 1 and 2. When the tongue 22 engages the blades 9 and 10 the blade 19 is received between the blades 5, 6 and 7, 8 and the blade 20 is received between the blades 1, 2. When the post 21 is withdrawn to bring its inner end flush with the insulating plate 14 the turning member has its range of rotation increased to one hundred and eighty degrees, the stationary blades 1 and 2 then serving as a motion limiting stop in place of the post 21. When the tongue 22 engages the blades 1 and 2, the blade 19 is engaged only between the blades 3, 4 and the blade 20 is engaged only between the blades 9, 10. Each set of coplanar pairs of stationary blades are so spaced apart that the blade upon the turning member complementary thereto will engage one of these pairs before becoming separated from the other. One or the other of two coplanar pairs of stationary blades thus cooperates with the complementary blade upon the turning member to receive axial thrusts upon the turning member which makes it unnecessary to employ any extraneous means to accomplish this result. This enables the employment of the plates 13 and 14 merely as lateral bearings for the turning member. These plates would permit the turning member to be axially movable were it not for the described interrelation of the contacting blades. Diagonally opposite pairs of stationary contacting blades that are not coplanar also cooperate with both blades upon the turning member to achieve the same result, one or the other of these pairs of blades cooperating with the complementary blade upon the turning member to receive end thrusts upon this member.

The anchoring rods 12 are desirably formed with threaded bores for the reception of metallic binding screws 23 and 24. The binding screws 23 serve to clamp circuit continuing conductors 25, 26, 27 and 28 into engagement with the inner riveted ends of the rods 12 that respectively assemble the blades 1, 2; 3, 4; 5, 6; and 7, 8, 9 and 10. When the switch is employed in connection with electricity meters, the binding screws 24 do not normally serve to connect any conductors with the rods 12 and the stationary contacting blades respectively pertaining thereto. When a meter is to be tested these screws are backed off sufficiently to enable conductors to be clamped between said rods and the heads of these screws.

Other distance preserving devices 28 are also desirably interposed between the plates 13 and 14, being preferably in the form of shouldered tubes of insulation, whose shoulders have abutting engagement with the plates and whose ends are snugly received within holes that are formed in the plates. The heads of the mounting screws 29 have clamping engagement with the insulating plate 14 and the stems of these screws pass through the tubes 28 into threaded engagement with the portions 30 of a support, which is desirably also inclusive of a mounting body 31 of insulation in which the parts 30, that are preferably metallic, are desirably molded. The mounting body 31 desirably also carries U-shaped contact terminals 32, 33, 34 and 35 that are respectively complementary to the circuit continuing contacts 25, 26, 27 and 28. These circuit continuing contacts are desirably in the form of resilient bars or arms whose unmounted ends are engageable with the aforesaid U-shaped contacts and cooper-

ate therewith to firmly fix the entire switching mechanism upon its support 31. The contacting ends of the circuit continuing contacts 25, 26, 27, 28 are sufficiently spaced apart from the inner insulating plate 13 and flexed away therefrom as to enable the same to have firm mechanical and electrical connection with the aforesaid complementary U-shaped terminal contacts, when the assembling screws 29 are screwed sufficiently home.

The switching mechanism is desirably placed within a casing, in which event the insulating supporting body 31 is desirably the back wall of the casing body, the top, bottom and side walls of the casing body being continued far enough forward to extend slightly in front of the knob 18'. The casing is provided with a cover 36, also preferably of insulation. This cover is provided with an opening 37 which receives the pin 18², that is eccentric with respect to the turning member 18, when the switch is adjusted to its normal working position. The shank of a bolt 38 is screwed into the pin 18², the head of the bolt clamping upon the cover to hold it in place, the cover having suitable formations 36' which prevent it from turning. The bolt 38 may have a perforated extension 38' which cooperates with a perforated lug 39 for holding a sealed wire which guards against the undetectable rotation of said bolt. The cover 36 is thus a holder for the turning member and the pin 18² and the cover portion at 37 are interengaging holding formations, eccentric to the axis of the turning member which serve to secure this turning member in its contact making position.

The circuit conductors may be led through the slots 40 in opposite sides of the box, or the circuit wires may be clamped into electrical connection with metallic rods 41 by means of the clamping nuts 42, Fig. 10. These rods are desirably also screwed into the inner ends of the bores of the rods 12 to bring these rods and the contacting blades in electrical connection therewith into electrical connection with said circuit conductors. When the construction of Fig. 10 is employed, the U-shaped members 43 are of slightly different shape from the U-shaped members 32 etc. and are placed reversely with respect to the latter U-shaped members to accommodate the rods 41. In the structure of Fig. 10 the circuit continuing conductors 25 etc. need not be employed since the inner riveted ends of the rods 12 are in direct engagement with the parts 43. The rear walls of the casing that contains the switch may be channeled as indicated at 44 for the reception of assembling bars and other parts that are employed when a number of these casings are assembled in a set, as set forth more particularly in my copending application Serial No. 382,645 filed August 11, 1929.

The insulating plate or guard 14 so effectively covers the contacts of the switch, particularly when the switch is enclosed in a casing, that the positions of the switch contacts cannot be observed, even though the cover 36 is removed, to determine the circuit adjustment effected by the switch. In order that the circuit adjustment effected by the switch may be known by mere observation, I provide the characteristics shown in Fig. 9. In this figure, the stationary member of the switch has lines 45, 46, 47 and 48 thereon, these lines being desirably routed in the plate or guard 14. Said lines extend from the regions of the binding screws 24 and the rods 12 toward the turning member of the switch. This turning member has lines 49 and 50 routed on the insulating body portion 18 thereof. When the switch is in normal position the line 49 fills the gap between the lines 45 and 46, being in consecutive relation with each line. The line 50 is then, also similarly related to the lines 47 and 48. When the switch is not in working position the lines 49 and 50 are separated from the lines related thereto. The user of the switch can instantly tell whether or not it is in its normal position by the relationship of the lines upon the moving and stationary members of the switch.

The switch of my invention may be put to many uses. Fig. 8 is a diagrammatic illustration of the switch of my invention as it may be employed in connection with an electric current consumption circuit the service meter in connection with such circuit and a rotating standard test meter when such is brought into connection with the system for the purpose of testing a service meter. In this figure, I have illustrated a single phase alternating current generator 51, though generators of other current may be employed, this generator being in circuit with a primary 52 of a transformer whose secondary 53 is included between the sides 54 and 55 of a load circuit. The load may be of any suitable sort, incandescent lamps 56 being illustrated in bridge of said load sides. The service meter illustrated is inclusive of a core 57 surrounded by a pressure winding 58 that is in bridge between the load sides and a core 59, which is surrounded by a current winding 60, which is normally included in circuit with the secondary 61 of a current transformer whose low wound primary 62 is serially included in the load side 54. The switch of my invention diagrammatically illustrated in Fig. 8 normally includes the current winding 60 in circuit with the transformer winding 61. The other parts of the service meter which are diagrammatically illustrated being so well known to those skilled in the art need not be described. The rotating standard test meter illustrated is in many respects similar to the service meter similar parts being given similar characters of reference with prime ex-

ponents added. The service meter is provided with switches 63, whereby its pressure winding 58 may be excluded from circuit. The pressure winding 58' of the test meter has its terminals supplied with clips 64, whereby this winding may be included in bridge between the load sides. The current winding 60' has its terminals supplied with clips 65 which may be clamped in electrical connection by means of the binding screws 24. The test meter has an artificial load, such as a bank of lamps 66, in circuit with its current winding 60'. Fig. 8 illustrates the test meter in testing relation with the service meter. 15 When the test meter is employed as illustrated a jumper 67 with clips 68 may be included in circuit with the current winding of the service meter.

Changes may be made without departing 20 from the invention.

Having thus described my invention, I claim:

1. An electric switch including a turning member and a stationary member, one of said members having thereon a plurality of metallic contacting blades; a plurality of pairs of metallic contacting blades upon the other member with the blades thereof spaced apart to receive the first aforesaid blades therebetween, each of the first aforesaid blades having a pair of contacting blades individual thereto, the contacting blades upon both members of the switch being so proportioned and related that some one of the first aforesaid blades is received between the contacting blades of the pair individual to it in all positions of the turning member, whereby axial movement of the turning member is guarded against; and a support in which the turning member is journaled and formed to permit the turning member to be axially movable were it not for the interrelation of the contacting blades.

2. An electric switch including a turning member and a stationary member, one of said members having a metallic contacting blade thereon; a plurality of coplanar pairs of stationary blades upon the other member, the blades of each pair being spaced apart to receive the first aforesaid blade therebetween, the contacting blades upon both members of the switch being so proportioned and related that the blade upon the first member is received between the contacting blades of some pair in all positions of the turning member, whereby axial movement of the turning member is guarded against; and a support in which the turning member is journaled and formed to permit the turning member to be axially movable were it not for the interrelation of the contacting blades.

3. An electric switch including a turning member and a stationary member, one of said members having thereon a plurality of metallic contacting blades; and a plurality of pairs

of metallic contacting blades upon the other member with the blades thereof spaced apart to receive the first aforesaid blades therebetween, each of the first aforesaid blades having a pair of contacting blades individual thereto, the contacting blades upon both members of the switch being so proportioned and related that some one of the first aforesaid blades is received between the contacting blades of the pair individual to it in all positions of the turning member, whereby axial movement of the turning member is guarded against, the interengaging blades receiving axial thrusts of the turning member to hold this member against axial movement.

4. An electric switch including a turning member and a stationary member, one of said members having a metallic contacting blade thereon; and a plurality of coplanar pairs of stationary blades upon the other member, the blades of each pair being spaced apart to receive the first aforesaid blade therebetween, the contacting blades upon both members of the switch being so proportioned and related that the blade upon the first member is received between the contacting blades of some pair in all positions of the turning member, whereby axial movement of the turning member is guarded against, the interengaging blades receiving axial thrusts of the turning member to hold this member against axial movement.

5. An electric switch including a turning member having thereon a plurality of contacting blades; and a stationary member having four pairs of contacting blades thereon, the blades of the pairs being spaced apart to receive the other blades therebetween, each of the latter blades having a pair of contacting blades complementary thereto, said pairs of blades having four metallic anchorages which are distributed about the turning member, each anchorage being formed and accessible for circuit connection therewith externally of the switch and including a rod passing through the related blades and rivet ended to clamp said blades together.

6. An electric switch including a turning member having thereon two contacting blades; and a stationary member having four pairs of contacting blades thereon, the blades of the pairs being spaced apart to receive the other blades therebetween, each of the latter blades having two pairs of contacting blades complementary thereto, said pairs of blades having four metallic anchorages which are distributed about the turning member, each anchorage being formed and accessible for circuit connection therewith externally of the switch and including a rod passing through the related blades, said rod being rivet ended to clamp the blades together and being provided with a threaded bore to receive a binding screw.

7. An electric switch including a turning member having thereon two contacting blades; and a stationary member having four pairs of contacting blades thereon, the blades of the pairs being spaced apart to receive the other blades therebetween, each of the latter blades having two pairs of contacting blades complementary thereto, said stationary member having a fifth pair of contacting blades which is also complementary to one of the complementary blades upon the turning member, this fifth pair of contacting blades being located abreast of one of the aforesaid pairs of contacting blades, said pairs of blades having four metallic anchorages formed and accessible for circuit connection therewith externally of the switch.

8. The structure of claim 7 wherein the anchorages are in the form of rods which pass through the blades to which they relate and are rivet ended to clamp these blades together.

9. The structure of claim 7 wherein the anchorages are in the form of rods which pass through the blades to which they relate and are rivet ended to clamp these blades together and are provided with threaded bores to receive binding screws.

10. An electric switch including a turning member having thereon two contacting blades; a stationary member having four pairs of contacting blades thereon, the blades of the pairs being spaced apart to receive the other blades therebetween, each of the latter blades having two pairs of contacting blades complementary thereto; and adjustable means for varying the range of movement of the rotatable member and serving, in one adjustment, to maintain a blade upon the turning member permanently in engagement with one of the pairs of contacting blades complementary to this contacting blade and in another adjustment permitting this contacting blade to move into and out of engagement with both of the pairs of contacting blades complementary thereto.

11. An electric switch including a turning member having a contacting blade thereon; a stationary member having two contacting blades thereon positioned to have one end of each engageable by the first mentioned contacting blade that is receivable between the blades of the stationary member, there being spacing means between the other ends of the blades of the stationary member; and clamping means for securing these other blade ends together with the spacing means therebetween.

12. An electric switch including a turning member having a contacting blade thereon; a stationary member having two contacting blades thereon positioned to have one end of each engageable by the first mentioned contacting blade that is receivable between the blades of the stationary member, there being

spacing means between the other ends of the blades of the stationary member; and a rod passing through said other ends of the blades upon the stationary member and serving to clamp these other blade ends, with the spacing means therebetween, in assembly.

13. An electric switch including a turning member having a contacting blade thereon; a stationary member having two contacting blades thereon positioned to have one end of each engageable by the first mentioned contacting blade that is receivable between the blades of the stationary member; and a metallic rod passing through said other ends of the blades upon the stationary member and serving to clamp these other blade ends, with the spacing means therebetween, in assembly, said rod being formed with a threaded bore for the reception of a binding screw.

14. An electric switch including a turning member having two contacting blades thereon and spaced apart longitudinally of the axis of the turning member; a stationary member having two pairs of contacting blades thereon, each blade upon the turning member having such a pair individual thereto, and being engageable with both blades of such pair, there being spacing means between the blades of each pair; and clamping means for securing the blades of each pair, together with the spacing means therebetween, in assembly.

15. An electric switch including a turning member having two contacting blades thereon and spaced apart longitudinally of the axis of the turning member; a stationary member having two pairs of contacting blades thereon, each blade upon the turning member having such a pair individual thereto, and being engageable with both blades of such pair, there being spacing means between the blades of each pair; and a rod passing through said other ends of the blades upon the stationary member and serving to clamp these other blade ends, with the spacing means therebetween, in assembly.

16. An electric switch including a turning member having two contacting blades thereon and spaced apart longitudinally of the axis of the turning member; a stationary member having two pairs of contacting blades thereon, each blade upon the turning member having such a pair individual thereto, and being engageable with both blades of such pair, there being spacing means between the blades of each pair; and a metallic rod passing through said other ends of the blades upon the stationary member and serving to clamp these other blade ends, with the spacing means therebetween, in assembly and provided with threaded bores to receive binding screws.

17. An electric switch including a rotating member having contacting blades thereon; a stationary member having a plurality of

sets of contacting blades thereon that are complementary to the aforesaid blades; and an anchorage for the blades of each set comprising a rod passing through the blades of such set and washers through which the rod also passes and which are alternated with the blades, said rod being pressed into holding relation with the associated blades and washers.

18. An electric switch including a movable member having a contact thereon; and a stationary member having a contact thereon, the first contact being movable into and out of engagement with the second, in combination with a casing for the switch having a cover portion, said movable switch member and cover portion having interengaging holding formations which serve to secure this switch member in one of its adjustments when the cover is applied.

19. An electric switch including a turning member having a contact thereon; and a stationary member having a contact thereon, the first contact being movable into and out of engagement with the second, in combination with a casing for the switch having a cover portion, said turning switch member and cover portion having interengaging holding formations eccentric to the axis of the turning member and which serve to secure this switch member in its circuit closing adjustment when the cover is applied.

20. The structure of claim 19 in which the holding formation upon the turning member is a pin and the holding formation upon the cover is a socket adapted to receive said pin.

21. The structure of claim 18, wherein the switch is secured to the body of the casing and a cover retaining device is assembled with the holding formation upon the movable switch member.

22. The structure of claim 19, wherein the switch is secured to the body of the casing and a cover retaining device is assembled with the holding formation upon the turning switch member.

23. The structure of claim 19 wherein the holding formation upon the turning member is a pin and the holding formation upon the cover is a socket adapted to receive said pin, and wherein the switch is secured to the body of the casing and a cover retaining device is assembled with the holding formation upon the turning switch member.

24. An electric switch including a movable member having a contact thereon, and a stationary member having a plurality of contacts thereon which are adapted to be bridged by the first contact, said stationary member having visual indications corresponding to the stationary contacts and both of said members having lines thereon which mate, when stationary contacts are bridged by the movable contact to form a continuous line visibly

connecting the indications of the bridged contacts.

25. An electric switch including a movable member having a contact thereon, a stationary member having a plurality of contacts thereon which are connectible in pairs by the first contact, and a visible terminal for each contact on the stationary member, said members each having lines thereon which mate, when a pair of contacts on the stationary member are connected by the contact on the movable member, to form a continuous line visibly connecting the terminals of the connected pair of contacts on the stationary member.

26. An electric switch comprising a rotatable contact, a plurality of stationary contacts arranged about said rotatable contact and connectible in pairs by the latter, a face plate, a terminal for each stationary contact extending through the face plate and visible on the front of the latter, and an operator for the rotatable contact also extending through the face plate, said operator and face plate having lines thereon which, when a pair of stationary contacts are connected by the rotary contact form a visible continuous line connecting the terminals of the connected stationary contacts.

In witness whereof I hereunto subscribe my name.
